SALES REGISTERING DEVICE FOR
GASOLINE PUMPS

Eugene F. Settlemire, Tucson, Ariz., assignor to Gas Register Corporation, Tucson, Ariz.
Filed Feb. 5, 1959, Ser. No. 791,339
14 Claims. (Cl. 235—94)

This invention relates to improvements in sales registering device for gasoline pumps.

The principal objects of this invention are:

First, to provide a sales registering attachment for gasoline pumps which will permit the sales by plural attendants to be individually recorded and accumulated for each attendant as a check on the sales that have been made and the monies for which they should be individually responsible.

Second, to provide a registering mechanism interlocked with the master register of a gasoline pump which is key actuated by different keys of different operators and which requires the actuation of one of these keys to operatively engage the register of the operator with the master register on the pump before the pump can be operated to deliver gasoline.

Third, to provide register mechanism attachable to gasoline pumps which will prevent careless or fraudulent delivery of gasoline by attendants without accounting for money received for the gasoline.

Fourth, to provide an interlock connection to the reset mechanism of the master register of a gasoline pump which will prevent the completion of the resetting operation and the releasing of the control switch of the pump until the interlock is released by actuation with a key.

Fifth, to provide individual registering mechanism of the type described which is relatively simple and inexpensive and easily attached to most of the gasoline pumps now in use.

Other objects and advantages of the invention will be apparent from a consideration of the following description and claims. The drawings, of which there are four sheets, illustrate a highly practical form of the invention as applied to a gasoline dispensing pump.

FIG. 1 is a front elevational view of a gasoline dispensing pump conventionally illustrating the operative parts thereof and the mounting of the register of the invention thereon.

FIG. 2 is an enlarged front elevational view of the registering mechanism of the invention with part of the cover and lock mechanism broken away to illustrate the interior arrangement of parts.

FIG. 3 is a fragmentary vertical cross sectional view taken along the plane of the line 3—3 in FIG. 2.

FIG. 4 is an enlarged fragmentary front elevational view of the master register and reset mechanism of the dispensing pump shown in FIG. 1 with the case of the pump broken away.

FIG. 5 is an enlarged side elevational view of the master register shown in FIG. 4 illustrating the interlocking connection of the invention, the view being taken along the plane of the line 5—5 in FIG. 4 and parts of the master register being shown conventionally or omitted.

FIG. 6 is a fragmentary cross sectional view through the reset mechanism taken along the plane of the line 6—6 in FIG. 4 and illustrating the first switch interlocking mechanism of the dispensing pumps.

FIG. 7 is a fragmentary cross sectional view through the reset mechanism taken along the plane of the line 7—7 in FIG. 4 and illustrating the second interlock of the master register reset mechanism in one phase of adjustment thereof.

FIG. 8 is a view corresponding to FIG. 7 but illustrating

2

the interlock mechanism in a different angularly adjusted phase of operation.

FIG. 9 is a fragmentary cross sectional view taken along the plane of the line 9—9 in FIG. 4 and illustrating the interlocking mechanism shown in FIGS. 7 and 8 from the opposite side.

In the operation of gasoline service stations in which several dispensing pumps are operated by several attendants, it has been found difficult and impractical to effectively check the accuracy and honesty of each attendant as the attendant might make a delivery of gasoline to a customer and fail to turn in part or all of the receipts for the delivery. While gasoline dispensing pumps currently in use are provided with a master register which shows the amount in gallons and the monetary value of each individual sale, these pumps are provided with interlock devices which require the amount of the first sale to be erased by zeroing the register prior to making a second sale. Thus unless each sale of each attendant is checked immediately upon completion, there has been no way of recording the sales which each attendant should be responsible for.

The present invention provides mechanism which necessarily requires that each attendant engage a key controlled counter or subregister assigned to him and operable only with his key prior to being able to dispense gasoline from the pump. A gasoline dispensing pump apparatus of the type commonly in use today is indicated generally at 1. Dispensing pumps of this type include a motor 2 driving the actual fluid pump 3 to deliver gasoline through the delivery hose 4. The motor 2 is under the control of an electric switch conventionally illustrated at 5 and this switch is commonly associated with a hook 6 on the side of the pump housing so that hanging up of the nozzle 7 of the hose automatically shuts off the motor 2 and the pump 3. In some installations a master pump delivers to a plurality of dispensing stations and hoses and is constantly in operation in which case the switch at the dispensing station actuates a valve in the individual hose line to permit deliveries through the hose. For the purpose of the present description the motor 2 and pump 3 in combination may be considered as a fuel supply means and the switch 5 may be considered as a switch connected to actuate and control the supply means. Practically every gasoline dispensing pump currently in use in this country includes a master register mechanism of the same design and construction. This register mechanism has one set of visible dials 8 which record or show the money value of gasoline delivered. A second set of dials 9 show the volume or gallons delivered. Since these dials are for the convenience of the customer and the attendant in completing each individual sale, mechanism is provided for returning the dials to zero prior to making a second sale and a crank 10 on the side of the pump case functions to zero the dials. Other registering devices and dials record the total money value and volume dispensing from the pump as will be described presently.

In order to record and accumulate the volume or value of sales made by each individual of several attendants, who may operate the pump at different times during the working period, the present invention provides an attendant recorder mounted in a case on top of the pump case 1 and indicated generally by the numeral 11. The case encloses an upright drive shaft 12 having a plurality of beveled driving gears 13 thereon. A flexible driving connection 14 from the drive shaft 12 connects to the master register mechanism as will be described in greater detail. The shaft 12 is thus driven in timed relation to either the money value dials 8 or the volume dials 9 whenever the pump is operated.

Pivots supported as at 15 on the back wall of the

case 11 are a plurality of counter bodies 16 having forwardly projecting end flanges 17 which support individual counter shafts 18. The shafts 18 carry dials 19 arranged to accumulate totals corresponding to the rotation of the shafts as will be understood. The ends of the shafts 18 carry bevel gears 20 which are swingable vertically with the counter bodies 16 into engagement with the drive gears 13 on the shaft 12. The dials 19 on the several counters are visible through openings 21 in the case 11 to permit ready checking of the total accumulated on each of the counters.

The counters 16 and the driven gears 20 carried thereby are moved selectively into engaged driving relation with the shaft 12 by means of several key operated locks 22 having integral pawls 23 that are rotated by means of keys 24 between the lower position shown at 23 and the elevated position shown at 23A in FIGS. 2 and 3. In moving to the elevated position each of the pawls 23 engages an arm 25 projecting laterally from an upright slide bar 26 mounted for limited sliding motion on the back wall of the casing by means of the pins 27 operating in slots 28. The slide bar 26 is urged lightly upwardly by a spring 29 but as will appear in greater detail presently, it is normally urged more strongly downwardly by spring tension applied to an operating wire 30 which extends into the pump housing 1. Pivotaly supported on each of the arms 25 at 31 is a locking cam 32. The cams 32 have noses 33 engageable with the underside of the flanges 17 on the right ends of the counter bodies to raise the counters and resist counter clockwise rotation of the cams as shown in FIG. 2. The cams 32 also have laterally projecting arms 34 that overlie and are engaged by the lock pawls 23 so that the lock cams 32 are rotated clockwise to raise the counters at the same time that the lift bar 25 is raised. Springs 35 bias the lock cams in a counter clockwise direction and springs 36 bias the counter bodies 16 downwardly.

Once any lock cam 32 is raised and its associated gear 20 engaged by actuation of one of the locks as at 23A the lock can be returned to deactuated position and the key removed so that the attendant can proceed with the business of operating the dispensing pump 1. The nose 33 will hold the actuated cam in position and will hold the counter body 16 in elevated position. By mechanism to be described, the lift 26 and the actuating wire 30 are held elevated until the register 8 is zeroed at which time downward motion of the lift bar permits disengagement of the nose 33 from the engaged counter.

Primary Register and Switch Interlocks

The primary register including the dials 8 and 9 must be returned to zero at the beginning of each sale, and in order to insure that the attendant zeroes the register, interlock mechanism is currently provided between the switch 5 and the register zeroing crank 10. Various forms of interlocking mechanism are provided by different manufacturers of gasoline pumps but since the interlock mechanism is directly associated with the individual register 11, an example of the switch interlock will be described in some detail. With reference to FIGS. 4 through 8 the frame 37 which supports the dials 8 and 9 of the primary register is illustrated as supporting the reset shaft 38 which is actuated through the spring pressed jaw clutch 39 from the reset crank 10. The right end of the shaft 38 as appears in FIG. 4 terminates adjacent the inside of the casing of the pump 1 and carries a rotatable cam 40 having a nose or lift 41 that rotates with the reset shaft 38. The switch 5 is mounted on the inside of the casing 1 and its actuating element or plunger 42 is positioned to be depressed by a switch actuating crank 43 rotatably mounted on the wall of the casing by a hub 44. Exterioly of the pump casing the hub 44 is provided with a manually operable crank 45. This crank is desirably associated with the previously described hook 6 so that

hanging up the nozzle 7 automatically turns the crank and the actuating member 43 to open the switch 5.

FIGS. 4 and 6 illustrate the switch interlock mechanism in the pump operating, closed condition of the switch. The dotted line positions in FIG. 6 indicate the off position of the switch and the engaged position of the interlock. When the switch actuating member 43 is turned by actuation of the crank 45 to the off position indicated at 43A, the hub 44 is turned to advance the notch 46 in the hub 44 to the position in 46A. In this position the notch 46 is open to receive the end of an interlock lever 47 which had previously been supported on the periphery of the hub. The dotted lines at 47A indicate the interlock engaged position of the lever. The lever 47 is pivotally supported on a stud 48 secured to the pump casing somewhat offset from the shaft 38. A toggle lever 49 swivelly mounted on the stud 48 is biased to an off-center position by the compression spring 50 compressed between the toggle lever and a fixed abutment 51. Pins 52 and 53 carried by the toggle lever alternatively engage the interlock lever 47 on opposite sides of the stud 48 to oppositely bias the interlock lever as will be described. In the full line position illustrated in FIG. 6, the pin 52 exerts a biasing force which moves the interlock lever from the full line position to the dotted position as soon as movement of the notch 46 permits such motion.

The forward or right end of the interlock lever 47 overlies the cam 40 on the reset shaft 38 and in the zeroed register operating position of the shaft and cam as illustrated, a projecting lug 54 on the interlock lever is received in a notch 55 in the cam as shown in FIG. 6. This performs the dual function of permitting motion of the interlock lever to the full line position illustrated and also prevents operation of the reset shaft 38 and the associated mechanism so long as the switch 5 is closed for the delivery of fuel. When the switch actuating member 43 is turned to off position as previously described the lug 54 moves to the dotted position illustrated at 54A releasing the cam 40 for reset operation.

The cam 40 and reset shaft 38 can be rotated only in the direction indicated in FIG. 6 by the clutch 39. Swivelly mounted on the reset shaft 38 at the outer end of the cam 40 is a keeper disc 56 having a radially projecting and axially turned pawl 57 thereon. The keeper disk is pressed into frictional driving engagement with the end face of the cam 40 by the cupped spring washer 58 shown in FIG. 4 between the keeper disk and the side wall of the casing 1. As the cam 40 is rotated while resetting the register dials 8, the pawl 57 is carried under the end of the interlock lever 47 and against the lug 54 as shown at 57A in FIG. 6. The keeper disk and its lug 57 are thus restrained against further rotation but the reset shaft 38 and cam 40 continue rotation through about 400° during which the nose 41 on the cam engages the pin 52 and throws the toggle lever 49 off-center with respect to the toggle spring 50 so that the pin 53 exerts a disengaging pressure against the left end of the interlock lever 47. Disengagement of the interlock lever from the notch 46 under this biasing pressure is prevented by engagement of the keeper 57 under the end of the lever 47 and by engagement of the lug 54 with the periphery of the cam 40.

When the resetting operation is complete the reset shaft 38 and cam 40 have traveled past the zero position of the register to an over-travel position and then returned as will be described to the zero position illustrated in full lines. The return rotation of the cam 40 frictionally returns the keeper lug 57 and realines the notch 55 with the lug 54 so that the interlock lever 47 moves out of the notch 46 and permits switch closing motion of the actuating member 43.

In order to exert the return rotating force on the reset shaft 38 from the over-travel position to the zero position of the register, the shaft 38 carries a cam disk 59 having a peripheral slot 60 therein. FIG. 8 shows the

cam and slot in the zeroed position of the mechanism and FIG. 7 shows the cam in partially rotated position obtained when the reset operation is started. A generally triangular crank 61 pivoted on the shaft 62 carries a pin or roller 63 projecting into the notch 60 and rotation of the cam 59 forces the roller out of the notch 60 and develops tension in the spring 64. Rotation of the crank 61 also moves the stud 65 out of the path of a cam 66 swivelly supported on the shaft 62.

Alongside of the cam disk 59 the reset shaft 38 carries a cam 67 positioned in the plane of the cam 66 and rotation of the cam 67 in the direction indicated in FIG. 8 brings the lift 68 into engagement with the nose 69 to rotate the cam 66 in a counter-clockwise direction as shown in FIGS. 7 and 8. Continued rotation of the reset shaft 38 through the previously described 400° causes the nose 70 on the cam 67 to engage the nose 69 and move the cam 66 to the position shown in FIG. 7. Thus in the initial rotation of the cam 67 the nose 70 passes under the stop 71 on the cam 66 but on the second rotation the nose 70 engages the stop 71 to define the limit of rotation of the reset shaft. The cam 66 is held in its locking position against the tension of the spring 72 by the pawl 73 pivoted at 74 and having a keeper notch 75 engageable with the cam 66 as shown in FIG. 7. A spring 76 pulls the pawl 73 into engagement with the cam 66.

Rotation of the cam 66 moves the axially projecting pin 77 carried thereby from the full line position illustrated in FIG. 9 to the position indicated by dotted lines at 77A. The pin 77 carries one end of a link 78 which has its other end slotted and passed over a pin 79 carried by a locking lever 80 freely pivotally supported on the shaft 38. The locking lever 80 is positioned closely alongside of one of the gears 81 of the register mechanism and this gear is provided with a locking stud 82 rotatable into the path of the lever 80. A spring 83 draws the pin 79 and the lever 80 into the path of the locking lug 82 when the cam 66 and the pin 77 carried thereby are advanced. The gear 81 and the locking lug 82 thereon are rotated during the reset operation, by mechanism not illustrated, in the direction indicated by the arrow in FIG. 9 to the over-travel position of the mechanism at which point the locking lug 82 and lever 80 are operative to prevent return of the dials from the over-travel position to zero position. Return rotation of the crank 61 and the pin or roller 63 thereon under the influence of tension in the spring 64 returns the cam plate 59 and the shaft 38 from the end of the over-travel position to the zero position of the reset shaft in the direction indicated by the arrow in FIG. 7. Simultaneously the nose 84 on the crank 61 strikes the pin 85 on the previously described latch 73 to disengage the keeper 75 from the cam 66 thus permitting the cam to return to normal position. This returns the pin 77 and link 78 to the full line position shown in FIG. 9 and releases the lock lever 80 from the lug 82 permitting the gear 81 to return (opposite to the direction of the arrow in FIG. 9) from its over-travel position to zeroed position.

The foregoing interlock mechanism is as stated an example of old and existing interlocks in the register mechanism of existing gasoline pumps. Normally the return of the mechanism from the over-travel position to the zeroed position is effected automatically as soon as the operator releases his hold on the reset crank 10. The additions of the present invention to this prior registering and interlocking mechanism will now be described.

Individual Recorder Interlock With Register

The interlock and driving connection between the individual recorder 11 and the master register of the pump is shown most clearly in FIGS. 4 and 5. To the existing framework 37 of the register the present invention adds the vertically extending strap 86 in laterally spaced relation beside the register. An angle bracket 87 is secured to an existing stud on the framework by the nut

88. A cam 89 is pinned to the reset shaft 38 for rotation therewith.

The bracket 87 forms a support for the bevel gear 90 in meshed driving engagement with the existing bevel gear 91 which drives the constantly engaged accumulator 92 of the master register. The gear 91 is driven through the shaft 93 by existing connections on the register which will not be described. The new bevel gear 90 is connected to the previously described drive shaft 14 which drives the individual recorders. It will thus be seen that whenever the pump is operating the money value of the gasoline dispensed will be accumulated in the accumulator 92 and the shaft 14 will be rotated in proportion to the money value accumulated and the volume of the fuel dispensed.

The strap 86 is provided with a forwardly extending arm 94 supporting the pivot pin 95 on which an interlock lever 96 is pivotally supported. The lever 96 carries a blocking pin 97 positioned to fall into locking engagement in the notch 98 in the cam 89 when the cam and the reset shaft 38 are advanced to the full over-travel position indicated at 98A in FIG. 5 as the master register is reset. A relatively heavy spring 99 biases the lever 94 and the pin 97 to interlocked position. A yoke 100 connects the lever 96 to the previously described actuating wire 30 which operates the slide bar 26 in the individual recorder.

Cycle of Operation

FIGS. 2, 4, 5, 6, 8 and 9 illustrate the mechanism in running condition in which the individual recorder 16A and its driving gear 20A are engaged with the drive shafts 12 and 14 and in which the switch 5 is closed and gasoline is being delivered as indicated by the numeral 13 on the master register dials 8 and the accumulator dials 92. When the attendant completes this particular sale and delivery and hangs the nozzle 7 on the hook 6, the switch actuating crank 45 is depressed rotating the switch actuator 43 to off position and permitting the interlock bar 47 to fall into the notch 46 under the influence of the toggle spring 50 shown in FIG. 6. In this condition the pump cannot be reactivated to make a second delivery or sale because of the interlock 46—47. The attendant who made the sale has had the amount thereof accumulated in his individual recorder 16A as appears in FIG. 2 and may leave the pump to perform other duties.

A second attendant approaching the pump to make a second sale must actuate the reset crank 10 and the reset shaft 38 to disengage the switch interlock bar 47 and due to the existing interlock mechanism shown in FIGS. 7, 8 and 9 this resetting operation must be completed to the overtravel position determined by the stops 70—71 in FIGS. 7 and 8 and the stops 80—82 in FIG. 9. The reset shaft is then pressed under returning spring tension of the spring 64 and crank 61 but automatic return from the over-travel position is prevented by engagement of the stop pin 97 in the notch 98 as shown in FIG. 5. As soon as the notch in the cam 89 registers with the pin 97, the relatively heavy spring 99 acting through the control wire 30 overcomes the relatively light spring 29 and depresses the slide bar 26 carrying with it the locking cam 24 and releasing the cam from engagement with the individual recorder 16A of the first attendant. The first attendant's recorder is thus automatically disengaged from the drive shaft 12 by operation of the spring 36 and he cannot be charged with a sale which he does not make.

The master register thus comes to rest in the over-travel position with the switch interlock bar 47 still engaged by reason of the position of the keeper 57 at 57A in FIG. 6. In order to proceed with the second sale the second attendant must insert his key 24 in the lock of the individual recorder assigned to him and actuate the lock and pawl 23 to raise the associated cam 32 and the slide bar 26. The action of the key overcomes the tension of the spring 99 and raises the interlock pin 97 out of the notch at 98A

thus freeing the reset shaft 38 and permitting the spring 64 and pin 63 to return the cam 59 and shaft 38 from the over-travel position to zeroed position as previously described. The switch interlock 47 is thus released and the second attendant can manually actuate the crank 45 to reclose the switch 5 and start the motor 2 for the second time. Simultaneously the cam 32 associated with the second attendant's lock is engaged under the recorder 16 of the second attendant who can now remove his key and proceed with the second delivery and sale. The engagement of the interlock pin 97 with the raised periphery of the interlock cam 89 prevents the spring 99 from depressing the control wire 30 and disengaging the individual recorder until this action is purposely accomplished by resetting the master register.

The foregoing sequence of operations achieves the object of the invention by insuring engagement of an individual recorder associated with an identifiable key prior to any delivery being made from the pump. The combination of interlocks also insures that the functions or operations of fully zeroing the individual sales dials 8 and 9 will be completely carried out prior to making any delivery and sale. The operator of a gasoline service station can thus be accurately advised of the amount of gasoline sold by each attendant and the attendants can be required to satisfactorily account for monies received.

What is claimed as new is:

1. In combination in a fuel dispensing device, fuel delivery means, a switch connected to actuate said delivery means, a registering device connected to said delivery means and having dials to register the amount of fuel delivered by said delivery means, a manually operable reset shaft connected to said registering device to return the register to zero and an overtravel position behind zero, a manually operable actuator positioned to close said switch, a first interlock connectable between said shaft and said actuator to lock the actuator in deactuated position when said shaft is in unactuated position and to unlock said actuator when said shaft is retracted to said overtravel position and re-advanced to zero position, a spring drive engageable with said shaft and a fixed part of said registering device to readvance said shaft from said overtravel position to said zero position, a second interlock engageable with said shaft and a fixed part of said register to lock said shaft in said overtravel position against the action of said spring drive, a control wire connected to said last interlock and spring biased to interlock engaging position, an individual recorder shaft connected to said register to be advanced therewith and having a plurality of gears, a plurality of individual recorders movably supported and having connecting gears movable into driving engagement with respective ones of said gears on said recorder shaft, a slide bar reciprocable transversely along side of said recorders between a retracted and advanced position and connected to said control wire to be biased by the spring thereof toward a retracted position, a second spring of lesser strength than the spring bias on said control wire and connected to said slide bar in opposition to the force exerted by said control wire, said second interlock having a cam absorbing the spring bias on said control wire in the released position of said second interlock whereby said slide bar is biased toward advance position by said second spring whenever said second interlock is released, a plurality of cams pivotally mounted on said slide bar and individually swingable into supporting engagement with a selected one of said recorders to support the recorder and the gear thereof in engagement with a gear on said recorder shaft, springs biasing said cams on said slide bar out of recorder engaging position, springs biasing said recorders out of driving engagement with the gears on said recorder shaft, said cams on said slide bar having retaining noses engageable with said recorders to hold the cams engaged therewith when said slide bar is advanced, and a plurality of locks actuatable by different keys and having pawls

rotatable into advancing engagement with said slide bar and said cam on said slide bar to raise the same to engage said connecting gears with said recorder shaft.

2. In combination in a fuel dispensing device, fuel delivery means, a switch connected to actuate said delivery means, a registering device connected to said delivery means and having dials to register the amount of fuel delivered by said delivery means, a manually operable reset shaft connected to said registering device to return the register to zero and an overtravel position behind zero, a manually operable actuator positioned to close said switch, a first interlock connectable between said shaft and said actuator to lock the actuator in deactuated position when said shaft is in unactuated position and to unlock said actuator when said shaft is retracted to said overtravel position and re-advanced to zero position, a spring drive engageable with said shaft and a fixed part of said registering device to readvance said shaft from said overtravel position to said zero position, a second interlock engageable with said shaft and a fixed part of said register to lock said shaft in said overtravel position against the action of said spring drive, a control wire connected to said last interlock and spring biased to interlock engaging position, an individual recorder shaft connected to said register to be advanced therewith and having a plurality of gears, a plurality of individual recorders movably supported and having connecting gears movable into driving engagement with respective ones of said gears on said recorder shaft, a slide bar reciprocable transversely along side of said recorders between a retracted and advanced position and connected to said control wire to be biased by the spring thereof toward a retracted position, a plurality of cams pivotally mounted on said slide bar and individually swingable into supporting engagement with said recorders to support the recorder and the gear thereof in engagement with a gear on said recorder shaft, springs biasing said cams out of recorder engaging position, springs biasing said recorders out of driving engagement with the gears on said recorder shaft, said cams on said slide bar having retaining noses engageable with said recorders to hold the cams on said slide bar engaged therewith when said slide bar is advanced, and a plurality of locks actuatable by different keys and having pawls rotatable into advancing engagement with said slide bar and said cams on said slide bar to raise the same to engage said connecting gears with said recorder shaft.

3. In combination in a fuel dispensing device, fuel delivery means, a switch connected to actuate said delivery means, a registering device connected to said delivery means and having dials to register the money value of fuel delivered by said delivery means, a manually operable reset shaft connected to said register to return the register to zero and an overtravel position behind zero, a manually operable actuator positioned to close said switch, a first interlock connectable between said shaft and said actuator to lock the actuator in deactuated position when said shaft is in unactuated position and to unlock said actuator when said shaft is retracted to said overtravel position and re-advanced to zero position, a spring drive engageable with said shaft and a fixed part of said registering device to re-advance said shaft from said overtravel position to said zero position, a second interlock engageable with said shaft and a fixed part of said register to lock said shaft in said overtravel position against the action of said spring drive, a control wire connected to said last interlock and biased to interlock engaging position, an individual recorder shaft connected to said register to be advanced therewith and having a plurality of gears, a plurality of individual recorders movably supported and having connecting gears movable into driving engagement with respective ones of said gears on said recorder shaft, a slide bar reciprocable transversely along side of said recorders between a retracted and advanced position and connected to said control wire to be biased by the spring thereof toward a retracted position, a second spring of lesser strength than the spring bias on said control wire and connected to said slide bar in opposition to the force exerted by said control wire, said second interlock having a cam absorbing the spring bias on said control wire in the released position of said second interlock whereby said slide bar is biased toward advance position by said second spring whenever said second interlock is released, a plurality of cams pivotally mounted on said slide bar and individually swingable into supporting engagement with a selected one of said recorders to support the recorder and the gear thereof in engagement with a gear on said recorder shaft, springs biasing said cams on said slide bar out of recorder engaging position, springs biasing said recorders out of driving engagement with the gears on said recorder shaft, said cams on said slide bar having retaining noses engageable with said recorders to hold the cams engaged therewith when said slide bar is advanced, and a plurality of locks actuatable by different keys and having pawls

70
75

tion and connected to said control wire to be biased thereby toward a retracted position, a spring of lesser strength than the bias on said control wire and connected to said slide bar in opposition to the force exerted by said control wire, said second interlock having a cam absorbing the bias on said control wire in the released position of said second interlock whereby said slide bar is biased toward advance position by said spring whenever said second interlock is released, a plurality of cams individually swingable into supporting engagement between said slide bar and selected one of said recorders to support the recorder and the gear thereof in engagement with a gear on said recorder shaft, means biasing said cams on said slide bar out of recorder supporting position, means biasing said recorders out of driving engagement with the gears on said recorder shaft, and a plurality of locks actuatable by different keys and having pawls rotatable into advancing engagement with said slide bar and said cams on said slide bar to raise the same to engage said connecting gears with said recorder shaft.

4. In combination in a fuel dispensing device, fuel delivery means, a switch connected to actuate said delivery means, a registering device connected to said delivery means and having dials to register the money value of fuel delivered by said delivery means, a manually operable reset shaft connected to said register to return the register to zero and an overtravel position behind zero, a manually operable actuator positioned to close said switch, a first interlock connectable between said shaft and said actuator to lock the actuator in deactuated position when said shaft is in unactuated position and to unlock said actuator when said shaft is retracted to said overtravel position and re-advanced to zero position, a spring drive engageable with said shaft and a fixed part of said registering device to re-advance said shaft from said overtravel position to said zero position, a second interlock engageable with said shaft and a fixed part of said register to lock said shaft in said overtravel position against the action of said spring drive, a control wire connected to said last interlock and biased to interlock engaging position, an individual recorder shaft connected to said register to be advanced therewith and having a plurality of gears, a plurality of individual recorders movably supported and having connecting gears movable into driving engagement with respective ones of said gears on said recorder shaft, a slide bar reciprocable transversely along side of said recorders between a retracted and advanced position and connected to said control wire to be biased thereby toward a retracted position, a plurality of cams individually swingable into supporting engagement between said slide bar and selected one of said recorders to support the recorder and the gear thereof in engagement with a gear on said recorder shaft, means biasing said cams out of recorder supporting position, means biasing said recorders out of driving engagement with the gears on said recorder shaft, and a plurality of locks actuatable by different keys and having pawls rotatable into advancing engagement with said slide bar and selected ones of said cams to raise the same to engage said connecting gears with said recorder shaft.

5. In combination in a fuel dispensing device, fuel delivery means, a switch connected to actuate said delivery means, a registering device connected to said delivery means and having dials to register the amount delivered by said delivery means, a reset shaft connected to said register to return the register to zero and an overtravel position behind zero, a manually operable actuator positioned to close said switch, a first interlock connectable between said shaft and said actuator to lock the actuator in deactuated position when said shaft is in unactuated position and to unlock said actuator when said shaft is retracted to said overtravel position and re-advanced to zero position, a spring drive engageable with said shaft and a fixed part of said registering device to re-advance said shaft from said overtravel position to said zero posi-

tion, a second interlock engageable with said shaft and a fixed part of said register to lock said shaft in said overtravel position against the action of said spring drive, a control wire connected to said last interlock and biased to interlock engaging position, an individual recorder shaft connected to said register to be advanced therewith and having a plurality of gears, a plurality of individual recorders movably supported and having connecting gears movable into driving engagement with respective ones of said gears on said recorder shaft, a slide bar reciprocable transversely along side of said recorders between a retracted and advanced position and connected to said control wire to be biased therewith toward a retracted, recorder disengaging position, a plurality of cams interlocking engageable between said slide bar and said recorders to hold previously engaged selected ones of said recorders engaged with said recorder shaft when said slide bar is advanced, means biasing said cams out of recorder engaging position, means biasing said recorders out of driving engagement with the gears on said recorder shaft, said cams being disengageable from between said recorders and said slide bar when said slide bar is retracted, and a plurality of locks actuatable by different keys and having pawls rotatable into advancing engagement with said slide bar and said cams to raise the same to engage said connecting gears with said recorder shaft.

6. In combination with a fuel dispensing device having a fuel delivery means, a switch connected to actuate said delivery means, a master register connected to indicate the amount delivered by said delivery means, a reset mechanism connected to return said register to zero and a first interlock connected between said switch and said reset mechanism to prevent closing said switch prior to resetting said register to zero, a second interlock engaged by partial actuation of said reset mechanism and operative to prevent complete operation of said reset mechanism, spring means connected to complete actuation of said reset mechanism when said second interlock is released, a release member connected to said second interlock, first spring means biasing said release member and said second interlock to interlocking position, second spring means of less strength than said first spring means biasing said release member to interlock releasing position, said second interlock having a cam sustaining said first spring means in the released position of said second interlock, a plurality of key operated elements engageable with said release member to release said second interlock, a common drive shaft connected to be advanced with said master register, a plurality of individual recorders each positioned adjacent one of said key operated elements to be moved thereby into driving engagement with said common shaft, a plurality of latching members each positioned to be engaged by one of said key operated elements and moved thereby to hold one of said individual recorders in driving engagement with said common shaft, said latching members having a driving connection to said release member to disengage the latch member out of latching relation to its recorder when said release member and said second interlock are moved to interlocking condition of said second interlock.

7. In combination with a fuel dispensing device having a fuel delivery means, a switch connected to actuate said delivery means, a master register connected to indicate the amount delivered by said delivery means, a reset mechanism connected to return said register to zero and a first interlock connected between said switch and said reset mechanism to prevent closing said switch prior to resetting said register to zero, a second interlock engaged by partial actuation of said reset mechanism and operative to prevent complete operation of said reset mechanism, spring means connected to complete actuation of said reset mechanism when said second interlock is released, a release member connected to said second interlock, first means biasing said release member and said second interlock to interlocking position, second

means of less strength than said first bias means biasing said release member to interlock releasing position, said second interlock having a cam sustaining said first bias means in the released position of said second interlock, a plurality of key operated elements engageable with said release member to release said second interlock, a common drive shaft connected to be advanced with said master register, a plurality of individual recorders each positioned adjacent one of said key operated elements to be moved thereby into driving engagement with said common shaft, a plurality of latching members each positioned to be engaged by one of said key operated elements and moved thereby to hold one of said individual recorders in driving engagement with said common shaft, said latching members having a driving connection to said release member to disengage the latch member out of latching relation to its recorder when said release member and said second interlock are moved to interlocking condition of said second interlock.

8. In combination with a fuel dispensing device having a fuel delivery means, a switch connected to actuate said delivery means, a master register connected to indicate the amount delivered by said delivery means, a reset mechanism connected to return said register to zero and a first interlock connected between said switch and said reset mechanism to prevent closing said switch prior to resetting said register to zero, a second interlock engaged by partial actuation of said reset mechanism and operative to prevent complete operation of said reset mechanism, spring means connected to complete actuation of said reset mechanism when said second interlock is released, a release member connected to said second interlock, first means biasing said release member and said second interlock to interlocking position, said second interlock having a cam sustaining said first bias means in the released position of said second interlock, a plurality of key operated elements engageable with said release member to release said second interlock, a common drive shaft connected to be advanced with said master register, a plurality of individual recorders each positioned adjacent one of said key operated elements to be moved thereby into driving engagement with said common shaft, a plurality of latching members each positioned to be engaged by one of said key operated elements and moved thereby to hold one of said individual recorders in driving engagement with said common shaft, said latching members having a driving connection to said release member to disengage the latch member out of latching relation to its recorder when said release member and said second interlock are moved to interlocking condition of said second interlock.

9. In combination with a fuel dispensing device having a fuel delivery means, a switch connected to actuate said delivery means, a master register connected to indicate the amount delivered by said delivery means, a reset mechanism connected to return said register to zero and a first interlock connected between said switch and said reset mechanism to prevent closing said switch prior to resetting said register to zero, a second interlock engaged by partial actuation of said reset mechanism and operative to prevent complete operation of said reset mechanism, spring means connected to complete actuation of said reset mechanism when said second interlock is released, a release member connected to said second interlock, a plurality of key operated elements engageable with said release member to release said second interlock, a common drive shaft connected to be advanced with said master register, a plurality of individual recorders each positioned adjacent one of said key operated elements to be moved thereby into driving engagement with said common shaft, a plurality of latching members each positioned to be engaged by one of said key operated elements and moved thereby to hold one of said individual recorders in driving engagement with said common shaft, said latching members having a driving connection to said

release member to disengage the latch member out of latching relation to its recorder when said release member and said second interlock are moved to interlocking condition of said record interlock.

10. In combination with a fuel dispensing device having a fuel delivery means, a switch connected to actuate said delivery means, a master register having dials connected to indicate the amount delivered by said delivery means, a reset mechanism connected to return said register dials to zero and a first interlock connected between said switch and said reset mechanism to prevent closing said switch prior to resetting said register dials to zero, a second interlock engaged by partial actuation of said reset mechanism and operative to prevent complete operation of said reset mechanism, means connected to complete actuation of said reset mechanism when said second interlock is released, a release member connected to said second interlock, a plurality of key operated elements engageable with said release member to release said second interlock, a common drive shaft connected to be advanced with said master register, a plurality of individual recorders each positioned adjacent one of said key operated elements to be moved thereby into driving engagement with said common shaft, a plurality of latching members each positioned to be engaged by one of said key operated elements and moved thereby to hold one of said individual recorders in driving engagement with said common shaft, said latching members having a driving connection to said release member to disengage the latch member out of latching relation to its recorder when said release member and said second interlock are moved to interlocking condition of said second interlock.

11. In combination with a fuel dispensing device having a fuel delivery means, a switch connected to actuate said delivery means, a master register having dials connected to indicate the amount delivered by said delivery means, a reset mechanism connected to return said register dials to zero and a first interlock connected between said switch and said reset mechanism to prevent closing said switch prior to resetting said register dials to zero, a second interlock engaged by partial actuation of said reset mechanism and operative to prevent complete operation of said reset mechanism, spring means to complete actuation of said reset mechanism when said second interlock is released, a release member connected to said second interlock, a plurality of key operated elements engageable with said release member to release said second interlock, a common drive shaft connected to be advanced with said master register, a plurality of individual recorders each positioned adjacent one of said key operated elements to be moved thereby into driving engagement with said common shaft.

12. A key operated individual sales recorder adapted to be connected to a dispensing device having a master register with a reset mechanism and an interlock restricting operation of the reset mechanism, said recorder comprising a case having a plurality of counters therein, a drive shaft in said case and extending therefrom for connection to said master register, a plurality of key operated locks in said case positioned to selectively move said counters into driving engagement with said shaft, a release member in said case having parts positioned to be engaged by each of said locks to advance said release member, a control element connected to said release member and extending from said case for attachment to said interlock on said register, means biasing said release member to advanced position, and holding elements movable into engagement between said counters and said release member by said locks to hold the counters engaged with said shaft, said holding elements having parts engaged by said release member upon movement thereof to retracted position to disengage the holding elements.

13. A key operated individual sales recorder adapted to be connected to a dispensing device having a master register with a reset mechanism and an interlock restricting operation of the reset mechanism, said recorder compris-

ing a case having a plurality of counters therein, a drive shaft in said case and extending therefrom for connection to said master register, a plurality of key operated locks in said case positioned to selectively move said counters into driving engagement with said shaft, a release member in said case having parts positioned to be engaged by each of said locks to advance said release member, a control element connected to said release member and extending from said case for attachment to said interlock on said register, and holding elements movable into engagement between said counters and said release member by said locks to hold the counters engaged with said shaft, said holding elements having parts engaged by said release member upon movement thereof to retracted position to disengage the holding elements.

14. A key operated individual sales recorder adapted for attachment to a dispensing device having a master register with a reset mechanism and a first interlock preventing a repeat operation of the device before the reset mechanism is actuated and a second interlock preventing actuation of said reset mechanism, said recorder comprising a case having a plurality of counters therein, a driving member in said case adapted for connection to said

register, a plurality of key operated locks having elements arranged to selectively drivingly engage said counters with said driving member, means engageable by said lock elements and extending from said case for connection to said second interlock to release said second interlock upon actuation of one of said locks, and means holding said counters engaged with said driving member and connected to said means engageable by said lock elements and extending from said case for connection to said second interlock to be released upon engagement of said second interlock.
